(57) **CLAIM**

We claim the ornamental design for an awning, as shown and described.

DESCRIPTION

FIG. 1 is a top perspective view of an awning in accordance with the present design;

FIG. 2 is a front view of the awning;

FIG. 3 is a right side view of the awning;

FIG. 4 is a rear view of the awning;

FIG. 5 is a left view of the awning; and,

FIG. 6 is a top view of the awning.

The broken lines depict portions of the awning that form no part of the claimed design.
